ATTORNEY.

UNITED STATES PATENT OFFICE.

RICHARD M. VAN VALKENBURGH, OF KANSAS CITY, MISSOURI, ASSIGNOR TO IRVING-PITT MANUFACTURING COMPANY, OF KANSAS CITY, MISSOURI, A CORPORATION OF MISSOURI.

LOOSE-LEAF BINDER.

Application filed June 4, 1926. Serial No. 113,662.

This invention relates to loose-leaf binders and especially to that type of binder employing a plurality of flexible sheet-holding members, such as tapes or thongs, and has for its primary object the provision of a novel means for winding said tapes and holding the same taut after the same have been wound the desired amount.

A further object of this invention is the provision of novel locking and actuating means for the thongs or tapes of loose-leaf binders.

Many minor objects and advantages of the instant invention will be set forth in the specification referring to the accompanying drawing in which but one embodiment of this invention is illustrated, and, in which:

Figure 1 is a fragmentary perspective view of a loose-leaf binder having tape actuating and locking means constructed in accordance with this invention.

Fig. 2 is an enlarged fragmentary sectional view taken along the edge of one of the tapes.

Fig. 3 is a fragmentary view taken along the winding and locking means looking toward the rear edge of the bound leaves.

Fig. 4 is a detailed view of the locking element taken on line IV—IV of Fig. 3.

Fig. 5 is an enlarged longitudinal sectional view showing the slidably supported locking and actuating means, and,

Fig. 6 is a detailed cross-section taken on line VI—VI of Fig. 5.

Similar reference numerals refer to like parts throughout the several views of the drawing and the numbers 7 and 8 designate the two covers of the binder respectively which are joined along their one edge by a flexible back, 9, which permits covers 7 and 8 to accommodate a varying number of sheets 10.

In binders of this type, it is desirable to hold sheets 10 between covers 7 and 8 by employing a plurality of flexible tapes or thongs 12 which are adapted to be wound or tightened and locked in place through suitable means hereinafter fully set forth.

In this instance, one end of each tape 12 is affixed to a leaf-clamping member 13 which may be hingedly affixed as at 14 to one of the covers 7. This hinge 14 permits the cover to freely swing from the closed to the open position without exerting a strain upon tapes 12. Each of tapes 12 extends through suitable perforations 15 of the leaves and is

threaded through a similar leaf-engaging member 16 which is likewise hingedly attached as at 17 to opposite cover 8. In threading each of tapes 12 through the leaf engaging member 16, the same should pass through each of a pair of parallel openings 18 and thence to the winding means whereby they are tightened to pull covers 7 and 8 together and leaf-clamping members 13 and 16 into the leaf-holding position shown in Fig. 2.

With the exception, perhaps, of the hingedly mounted leaf clamping members, the structure of a loose-leaf binder set forth to this point is well known in the art.

Simple, effective and durable means for winding the tapes and for locking the winding element in place after it has pulled the tapes sufficiently, constitutes the salient features of this invention, and the same may be constructed, as shown, to include a rotatable tube 19 mounted for free and unrestricted rotary motion in bearings 20, one of which may be rigidly carried by cover 8 adjacent each of its two edges and at a point near the line of meeting of back 9 therewith. Each bearing 20 is curved upwardly and outwardly as shown in Fig. 4 to support tube 19 behind leaves 10 where it will be completely covered by the flexible back 9. It is to be noticed that this tube and the bearings 20 will not interfere with leaves 10 or the operation of leaf-engaging members 13 and 16.

Tube 19 has an integral flange 21 formed at each of its ends to engage the edge of each bearing 20, respectively, and which precludes the slightest longitudinal movement. Each of the plurality of tapes 12 is fastened to tube 19 in any suitable manner. In this instance, the tube is provided with a pair of diametrically opposite slots through which the end of tape 12 is passed to be sewed together, as shown in Fig. 2. It is understood, however, that each of the tapes 12 may be affixed to tube 19 in any suitable manner. This particular construction and many other ways of affixing these tapes will permit of their being wound upon tube 19 when it is rotated in either direction.

To rotate the winding tube 19 and lock it in the desired position without imparting longitudinal movement thereto, a rod 22 is mounted therein for longitudinal movement which has integral lugs 23 extending laterally therefrom which are slidably positioned within co-acting longitudinal slots 24 formed

in the wall of tube 19. These slots 24 extend inwardly from one end of the tube, limit the longitudinal movement of rod 22 and permits of its rotating the winding shaft after 5 longitudinal movement is imparted to the rod. The locking means formed integrally with the rod engages a co-acting stationary member; which, in this instance, is bearing 20 supporting the slotted end of tube 19. This 10 locking means may be constructed, as shown, as member 25 having a plurality of teeth 26 formed thereon which extend substantially parallel to rod 22 and which are spaced apart therefrom to permit the same to over-lap tube 15 flange 21 and the circular portion of bearing 20 and engage a portion of bearing 20 adjacent its cylindrical end between a pair of adjacent teeth as shown in Figs. 4 and 5. These teeth 26 engage the bearing or any 20 other suitable stationary element which may be provided for that purpose, when rod 22 has reached the end of its travel in one direction. Thus, when it is desired to operate the device and tighten tapes 12 when the elements are 25 in the position shown in Fig. 1, it is but necessary to grasp member 25 and turn it in the desired direction. This turning of member 25 will impart a like movement to rod 22 which will, in turn, rotate tube 19 by engaging the same through lugs 23 and slot 24. When the tube 19 has been turned sufficiently 30 to tighten all of the tapes 12, an inward thrust on member 25 will impart longitudinal rectilinear movement to the rod 22 and a tooth 35 26 will engage on each side of bearing 20 to preclude further rotation of rod 22 and also tube 19.

If desired, tube 19 may be formed of a shaft which is merely hollow for a portion of 40 its length, but it is preferred, in practice, to use the tube 19. The flanges 21 are turned out at each end and rod 22 is inserted with its lugs 23 sliding in slots 24 before the bearing 20 adjacent the slotted end is curled over the 45 same. Lug 23 will engage the edge of bearing 20 when member 25 is pulled outwardly from the locked to the unlocked position and limit further movement in that direction.

It is understood that many modifications 50 may be made in constructing the device without departing from the scope of the appended claims.

What I desire to secure by Letters Patent is:

55 1. In a loose-leaf binder of the character described, a rotatable winding tube, tapes secured to said tube, a member mounted within said tube for turning the same in either direction to wind the tapes thereon, a stop mounted on said binder and means on said member to engage said stop.

60 2. In a loose-leaf binder of the character described, a rotatable winding tube, bearings for said tube and a member slidably mounted for longitudinal movement within the tube,

said member having a lateral extension on its outer end for engaging one of said bearings to lock said winding tube against rotation.

3. In a loose-leaf binder of the character described, a rotatable tube, a winding rod 70 slidably mounted for longitudinal movement within the tube and means for limiting the longitudinal movement of said rod to prevent withdrawal of said rod from said tube.

4. In a loose-leaf binder of the character 75 described, a tape-winding tube having longitudinally extending guide slots formed therein, an operating rod slidably mounted within said tube having means for engaging said slots to rotate said tube and means for locking 80 said rod and tube against rotation relative to said binder.

5. In a loose-leaf binder of the character described, a bearing, a rotatable tube carried by said bearing, a rod mounted for longitudinal movement within said tube and projecting from one end thereof, means for limiting the longitudinal movement of said rod and means integral with the said rod adapted to engage said bearing to lock said tube 90 against rotation.

6. In a loose-leaf binder of the character described, a rotatable tape-winding member, actuating means carried by said member for rotation therewith and for relative longitudinal movement therealong, a stop, mounted on said binder and a plurality of locking elements integral with said actuating means for selectively engaging said stop. 95

7. A loose-leaf binder comprising a pair of 100 covers, a flexible back connecting said covers, a leaf-clamping member hingedly secured to each cover, tapes adapted to draw said leaf-clamping members against the leaves to hold the same in position, a bearing adjacent each 105 edge of one cover, a tape-winding tube journaled in said bearings, said tapes being connected to said tube, and means slidably mounted within said tube for locking it against rotation, said means having a lateral extension 110 positioned to engage one of said bearings when at the end of its movement in one direction.

8. A loose-leaf binder comprising a pair of 115 covers, a flexible back connecting said covers, a leaf-clamping member hingedly secured to each cover, tapes connecting said leaf-clamping members and adapted to draw the same to the leaf-holding position, a bearing rigid with one cover adjacent each edge thereof, a tape-winding tube rotatably journaled in said bearings and means mounted within said tubes for rectilinear movement and having a projection at one end movable therewith to engage one of said bearings to lock the tube 120 against rotation. 125

9. A tape winding means for loose leaf binders including a tubular member, a slot formed in the wall of said tubular member, a longitudinally movable member carried with- 130

in said tubular member, said last named member engaging said slot and rotatable with said tubular member.

10. A tape winding means for loose leaf binders including a tubular rotatable member, a slot formed in the wall of said tubular member and a member carried within said tubular member having a guide lug slidable along said slot.

10 11. In a loose leaf binder, a winding tube, a fixed top mounted on said binder, a member slidably mounted in said tube at one end thereof, said member having means at its inner end to engage the tube to rotate the same, and 15 having means at the other end to engage said stop to lock said tube against rotation.

12. In a loose leaf binder, a winding tube, a stop mounted on said binder adjacent one end of said tube, a member slidably mounted at one end in said tube, said member having an extension on its other end for engaging said stop.

20 13. In a loose-leaf binder of the character

described, a rotatable winding tube, a stop mounted on said binder, and common means 25 extending within the tube for turning said tube or for locking the same against rotation upon engagement with said stop.

14. In a loose-leaf binder of the character described, a rotatable winding tube, a stop 30 mounted on said binder adjacent one end of said tube, means slidably mounted for longitudinal movement therein and having an extension adapted to engage said stop to lock said tube against rotation.

15. In a loose-leaf binder of the character described, a rotatable tape winding tube, a winding and locking rod mounted within said tube for longitudinal movement, a stop 40 mounted on said binder, locking means carried by said rod and movable toward the locked position against said stop while the rod is rotating said winding tube.

In testimony whereof I hereunto affix my signature.

RICHARD M. VAN VALKENBURGH.
